LAVATORY WASTE AND FITTING

Frank G. Bretz, Kohler, Wis.

Application January 16, 1933, Serial No. 651,970

8 Claims. (Cl. 4—200)

My invention relates to improvements in lavatory wastes and fittings therefor.

Waste valve fittings are customarily positioned in a housing formed separately from the lavatory. To prevent corrosion, both the waste valve fitting and the housing are customarily made of brass, polished and nickel or chromium plated to improve the appearance. Brass is a relatively expensive metal, particularly when polished and plated, and it is an object of my invention to reduce the cost of manufacture by greatly lessening the amount of brass which must be used, accomplishing this result by providing such variations of the usual construction of waste fittings as will permit the housing to be cast integral with the lavatory.

Constructions such as previously described also require the formation of several joints which are not only unsightly and potential sources of leakage, but are expensive to produce since their production requires considerable tapping, threading and machining. The necessity of assembling several joints also materially increases the time necessary for installation of the fitting. It is another object of my invention to reduce the number of joints necessary, improving the appearance and materially reducing the cost of manufacture and installation.

Another object of my invention is to provide a construction of valve which may be readily disassembled for cleaning.

A further object of my invention is to provide an improved coupling between the lift rod and the valve actuating mechanism.

I attain these objects by the use of the mechanism illustrated in the accompanying drawings, in which Figure 1 is a side sectional elevation of a lavatory showing one form of the improved waste and fitting, Fig. 2 is a sectional view of the connection between the lift rod and the valve actuating member, Fig. 3 is a side sectional view of a modified form of waste and fitting, and Fig. 4 is a sectional view thereof along the lines 5—5 of Fig. 3.

Similar numerals refer to similar parts throughout the several views.

Although the improvement is herein illustrated and described with particular reference to its use in connection with lavatories, it is adaptable to other plumbing fixtures such as sinks, etc., and they are considered equivalents of the term "lavatory" as used herein.

In the drawings the numeral 1 indicates a lavatory formed with an integrally cast overflow channel 2 which has communication with the

bowl or basin 4 of the lavatory through the overflow aperture 3 positioned near the top of said basin. The overflow channel 2 has communication with the housing 5 forming part of the overflow channel 2, also cast integral with the lavatory and adapted to enclose the waste plug valve as hereinafter described. The lavatory bowl 4 has a waste aperture 6 at the bottom thereof communicating with the housing 5. As will be seen from the illustration the overflow channel is positioned at the rear of the fixture and extends upwardly from the waste aperture to the outlet aperture. An annular valve seat 7 is positioned in the waste aperture 6 and is provided with a tubular tailpiece 8 extending downwardly and through the drain aperture 9 positioned to register with the waste aperture 6. A nut 10 threaded on the tailpiece 8 holds the valve seat and tailpiece in position and compresses the gasket 11 which seals against leakage. The tailpiece 8 is apertured between the waste aperture 6 and the drain aperture 9 to permit the passage of fluid from the overflow channel and the hereinafter described valve actuating means therethrough. The nut 10 is provided with an internally threaded skirt 12 to which is attached the drain pipe 13. Thus the attachment of the drain pipe requires but a single joint. The tubular waste plug valve 14 extends into said channel and said tailpiece is slidably mounted in the tailpiece and adapted to seat on the valve seat 7 and is provided with a number of slots or openings 15 which furnish a passageway for the water when the valve is in the raised position shown by the dotted line of Fig. 1.

As aforementioned, the housing 5 is cast integral with the lavatory 1. The housing 5 is provided with the inwardly extending shoulder or boss 20 having the externally opening bore 21, threaded at 19, formed therein. The shoulder 20 is likewise provided with a bore or aperture 35 of smaller diameter than the bore 21 and opening internally of the housing 5. The bore 21 and bore 35 connect to form a socket for the ball 22 of the actuating member 23 which extends through said bores to engage the valve 14. The bore 35 opens into the channel 2 at a point above the juncture of the drain pipe 13 with the tailpiece 8 at a point approximately in the same lateral plane as the aperture in the valve tailpiece and is preferably positioned in the rear wall of the channel 2. Thus the entire valve operating mechanism is positioned on the fixture itself rather than in a separate housing, making a more compact and sightly installation, decreasing the

number of joints, eliminating much expensive polished and plated material and greatly reducing the cost of manufacture. It will be understood that the ball 22 may be semi-spherical instead of spherical as shown, or any other construction which will provide a swivel or pivoted joint may be used. The bore 21 and shoulder 29 may, if desired, be formed separately from the housing 5 and inserted through a suitable aperture therein. An externally threaded nut 24 provided with an inwardly extending shoulder 25 is threaded into the nut 19. A coil spring 26 abuts the shoulder 25 and bears against the ball 22. The packing 27 forms a seat for the ball 22 and prevents escape of water around the ball. The lift rod 28 extends through the lavatory 1 and is held in position in any suitable manner such as by the guide nut 29.

A connecting link 30 is provided with an aperture 31 through which the actuating member 23 protrudes, thus vertical movement of the link 30 is transmitted to the actuating member 23. The link 30 is also provided with an aperture 32. A shoulder nut 33 is threaded on the lift rod 28 with the shoulder uppermost, the dimensions of the nut being such that the shoulder will overlie the aperture 32 while the main or body portion of the nut will enter this aperture. A similar nut 34 is positioned upon the lift rod 28 with the shoulder lowermost and is turned up to abut the nut 33. This allows the lift rod to be rotated, as often accidentally occurs in practice, without varying the vertical adjustment of the link 30 or causing it to become disengaged from the lift rod, as occurs when the link is threaded directly thereto. The slight space between the nuts 33 and 34 and the aperture 32 provides the coupling with some degree of flexibility without objectionable looseness.

The operation of the valve will be apparent from the foregoing description. Lowering the lift rod 28 acts through the link 30 to depress one extremity of the actuating member 23 and raise the opposite extremity, the actuating member being pivotally mounted at the ball 22, raising the valve 14 to the position shown by the dotted line of Fig. 1. Raising the lift rod reverses this action and causes the valve to close. The coil spring 26 holds the ball 22 in engagement with the packing 27 and prevents leakage of water. The nut 24 retains the spring 26 and the ball 22 in position and also provides a means of adjusting the pressure created by the spring 26 on the ball 22.

The entire construction may be readily disassembled by removing the nut 24 when the coil spring 26 and the entire actuating member 23 may be withdrawn. The valve 14 may then be removed and cleaned. A suitable tool may be inserted through the aperture 35, through which the actuating member 23 ordinarily extends, for the purpose of cleaning the inside of the housing 5. This is an important feature, since valves frequently become clogged with hair, sediment, etc., and as ordinarily constructed there is no practical method of cleaning out the valve when this occurs.

It will be seen from the foregoing that I have constructed a valve which is simple in operation and economical to manufacture, since the valve housing is formed integral with the lavatory, as is the seat or socket for the valve actuating mechanism. The amount of expensive brass which must be used is reduced to a minimum, and only one joint is required to attach the drain pipe to

the tailpiece of the valve, reducing the amount of tapping and machining required.

A modified form of my invention is shown in Figs. 4 and 5. In this form the housing 5 is apertured at 36 and 37 to permit the positioning of the sleeve bolt 38 transversely of the housing. The bolt 38 is secured by the nut 39, gaskets 40 and 41 being provided to prevent leakage. The bolt 38 is provided with the bore 42, adapted to receive the spindle 43. The finger 44 is splined or otherwise non-rotatably attached to the spindle 43 and passes through the tailpiece 8, it being understood that the tailpiece is apertured for this purpose and for the purpose of allowing water to pass from the housing 5 into the bore 15 thereof.

The finger 44 has an enlarged or bulbous end portion 45 adapted to fit in a slot or aperture in the waste plug valve 14 whereby vertical movement of the finger causes a corresponding vertical movement of the waste plug valve 14 and raises it from or seats it on the valve seat 7. A crank arm 46 is splined or otherwise non-rotatably attached to the spindle 43. The opposite extremity of the crank arm 46 terminates in a yoke 47. A clamp 48 has a trunnion 49 extending through an aperture in the yoke 47. A set screw 50 having a conical point extends through an aperture in the opposite side of the yoke 47 and is threaded in and extends through the clamp 30 48. The set screw 50 acts as a trunnion so that the clamp 48 is pivotally mounted in the yoke 47 and also acts as a clamping means for the spring 51. The spring 51 is attached, by means of suitable clamping means 52, to the lift rod 28 which extends through the lavatory 1. The lift rod 28 may extend through the faucet 53 as illustrated.

From the above description it will be evident that manipulation of the lift rod 28 will act through the spring 51, crank arm 46, spindle 40 43 and finger 44 to raise and lower the waste plug valve 14. The spring 51 creates a tension and sufficient friction to prevent the waste plug valve from closing by the force of gravity, and is advantageous with this type of construction. 45 However, the form of coupling illustrated in Figs. 1 and 3 may be used if desired.

The construction above described possesses many of the advantages of the preferred form of my invention, shown in Fig. 1, such as reduction of the amount of expensive metal required, reduction of the number of joints, etc. All of the operating mechanism, with the exception of the waste plug valve 7 and the finger 44, is located outside of the water passageways, thus 55 there are no obstructions in the main water passageways likely to cause clogging and the area subject to fouling by waste water is materially reduced.

I claim:

1. Means for attaching a lift rod to valve actuating mechanism comprising a lift rod, a link provided with an aperture, a nut threaded on said lift rod, said nut having a shoulder adapted to overlie the aforesaid aperture, and a body portion adapted to enter said aperture, and a second nut threaded on said lift rod and provided with a shoulder adapted to overlie the said aperture and a body portion adapted to enter said aperture, the position of the aforesaid shoulders being such as to overlie opposite sides of said link.

2. In combination in a lavatory waste fitting, a link provided with an aperture, a lift rod adapted to enter said aperture, a nut threaded 75

on said lift rod and having a body portion adapted to enter said aperture, and a shoulder adapted to overlie one side of said link adjacent said aperture and a second nut threaded on said lift rod and having a body portion adapted to enter said aperture and a shoulder adapted to overlie the opposite side of said link, said nuts being free to rotate in said aperture without causing vertical movement thereof on said lift rod.

10 3. In combination, in a lavatory waste fitting, a lift rod, a link, and means attached to said lift rod for connecting said lift rod to said link, said means being freely rotatable within said link and having portions adapted to overlie opposite 15 sides of said link whereby to transmit vertical movement of said lift rod thereto.

movement of said lift rod thereto.

4. In combination, in a lavatory waste fitting, a lift rod, a link, and means having threaded attachment to said lift rod and positioned within an aperture in said link for connecting said lift rod to said link, said means being freely rotatable within said link and having portions adapted to overlie opposite sides of said link whereby to transmit movement of said lift rod in the direction of the longitudinal axis thereof to said link without rotation of said lift rod being transmitted to said link or causing longitudinal movement of said connecting means upon said lift rod.

5. In combination, a plumbing fixture, a basin
30 therein; an overflow aperture positioned near
the top of said basin; a waste aperture positioned
at the bottom of said basin; a channel formed
integrally with said fixture, positioned at the
rear thereof, extending upwardly from said waste
35 aperture to said outlet aperture and communicat-
ing with said waste aperture and said overflow
aperture; a drain aperture in said channel regis-
tering with said waste aperture; an annular valve
seat positioned in said waste aperture and pro-
40 vided with a tubular tailpiece extending through
said drain aperture for attachment to a drain
pipe; an aperture in said tailpiece positioned be-
tween said waste aperture and said drain aper-
ture, communicating with said channel and
45 adapted to allow the passage therethrough of
valve actuating means, a tubular valve adapted to
seat on said valve seat, having a portion extend-
ing into said tailpiece and said channel, said
valve being slidably mounted in said tailpiece, a
50 bore extending through the rear wall of said
channel at a point approximately in the same
lateral plane as said aperture in the valve tail-
piece and above the point of juncture of said tail-
piece and said drain and in a vertical plane ap-
55 proximating the center of said channel, extend-
ing between the interior of said channel and
the exterior thereof; a shoulder in said bore; valve
actuating means comprising a central portion
having an arcuate surface adapted to abut said
60 shoulder in said bore; a portion extending through
said bore, said channel and said tailpiece, and
adapted to engage said valve and a portion ex-
tending through said bore to the exterior of said
channel, a lift rod extending through said fix-
65 ture and slidably mounted thereon; means for
connecting said lift rod and said extending por-
tion of said valve actuating means and retaining
means having engagement with said bore and
adapted to retain said arcuate portion of said
70 valve actuating means in engagement with said
shoulder, said retaining means and said valve
actuating means being removable through said
bore, whereby to render the interior of said chan-
nel accessible through said bore for cleaning.

therein; an overflow aperture positioned near the top of said basin; a waste aperture positioned at the bottom of said basin; a channel formed integrally with said fixture, positioned at the rear thereof, extending upwardly from said waste aperture to said outlet aperture and communicating with said waste aperture and said overflow aperture; a drain aperture in said channel registering with said waste aperture; an annular valve seat positioned in said waste aperture and 5 provided with a tubular tailpiece extending through said drain aperture for attachment to a drain pipe; an aperture in said tailpiece positioned between said waste aperture and said drain aperture, communicating with said channel and 10 adapted to allow the passage therethrough of valve actuating means, a tubular valve adapted to seat on said valve seat, having a portion extending into said tailpiece and said channel, said valve being slidably mounted in said tailpiece, a 15 bore extending through the rear wall of said channel at a point approximately in the same lateral plane as said aperture in the valve tailpiece and above the point of juncture of said tailpiece and said drain and extending between the interior of said channel and the exterior 20 thereof; a shoulder in said bore; valve actuating means comprising a central portion having an arcuate surface adapted to abut said shoulder in 25 said bore; a portion extending through said bore, said channel and said tailpiece, and adapted to engage said valve and a portion extending through said bore to the exterior of said channel, a lift rod extending through said fixture and slidably mounted thereon; means for connecting said lift rod and said extending portion of said valve actuating means and retaining means having engagement with said bore and adapted to retain 30 said arcuate portion of said valve actuating means in engagement with said shoulder, said retaining means and said valve actuating means being removable through said bore, whereby to render the interior of said channel accessible through said bore for cleaning. 35 40

7. In combination, a plumbing fixture, a basin 45
therein, an overflow aperture positioned near the
top of said basin; a waste aperture positioned at
the bottom of said basin; a channel formed in-
tegrally with said fixture, positioned at the rear
thereof, extending upwardly from said waste ap-
erture to said outlet aperture and communicat-
ing with said waste aperture and said overflow
aperture; a drain aperture in said channel reg-
istering with said waste aperture; an annular
valve seat positioned in said waste aperture and 50
provided with a tubular tailpiece extending
through said drain aperture for attachment to
a drain pipe; an aperture in said tailpiece pos-
itioned between said waste aperture and said drain
aperture, communicating with said channel and 55
adapted to allow the passage therethrough of
valve actuating means, a tubular valve adapted
to seat on said valve seat, having a portion ex-
tending into said tailpiece and said channel, said
valve being slidably mounted in said tailpiece; a
bore extending through the rear wall of said 60
channel at a point approximately in the same
lateral plane as said aperture in the valve tail-
piece and extending between the interior of said
channel and the exterior thereof; a shoulder in
said bore; valve actuating means comprising a 65
central portion having an arcuate surface adapt-
ed to abut said shoulder in said bore; a portion
extending through said bore, said channel and
said tailpiece, and adapted to engage said valve 70
75

and a portion extending through said bore to the exterior of said channel, a lift rod extending through said fixture and slidably mounted thereon; means for connecting said lift rod and said extending portion of said valve actuating means and retaining means having engagement with said bore and adapted to retain said arcuate portion of said valve actuating means in engagement with said shoulder, said retaining means and said valve actuating means being removable through said bore, whereby to render the interior of said channel accessible through said bore for cleaning.

8. In combination, a plumbing fixture, a basin therein; an overflow aperture; a waste aperture; a channel formed integrally with said fixture, communicating with said waste aperture and said overflow aperture; a drain aperture in said channel registering with said waste aperture; a valve seat positioned in said waste aperture and provided with a tailpiece extending through said drain aperture for attachment to a drain pipe; an aperture in said tailpiece positioned between said waste aperture and said drain aperture, communicating with said channel and adapted

to allow the passage therethrough of valve actuating means, a valve adapted to seat on said valve seat, having a portion extending into said tailpiece and said channel; a bore extending through said channel at a point approximately in the same lateral plane as said aperture in the valve tailpiece and above the point of juncture of said tailpiece and said drain pipe and in a vertical plane approximating the center of said channel, and extending between the interior of said channel and the exterior thereof; a shoulder in said bore; valve actuating means comprising a central portion having an arcuate surface adapted to abut said shoulder in said bore; a portion extending through said bore, said channel and said tailpiece, and adapted to engage said valve and a portion extending through said bore to the exterior of said channel, a lift rod; means for connecting said lift rod and said extending portion of said valve actuating means and retaining means having engagement with said bore and adapted to retain said arcuate portion of said valve actuating means in engagement with said shoulder.

FRANK G. BROTHZ. 25
